(57) **CLAIM**

The ornamental design for a closure for a container, as shown and described.

DESCRIPTION

FIG. 1 is an isometric view taken from the top front and right side of my new design of a closure for a container, and FIG. 1 shows the closure with the lid closed before initial actuation or opening of the closure;

FIG. 2 is an isometric view taken from the top rear and right side thereof;

FIG. 3 is a top plan view thereof;

FIG. 4 is a front elevational view thereof;

FIG. 5 is a right side elevational view thereof, the left side elevational view thereof being a mirror image; and, FIG. 6 is a rear elevational view thereof.

The undisclosed bottom view of the closure is unornamented, is not visible to the consumer when the closure is installed on a container (not shown), and forms no part of the claimed ornamental design.
